US00D923339S

(12) **United States Design Patent** (10) Patent No.: **US D923,339 S**
Okai et al. (45) Date of Patent: **** Jun. 29, 2021**

(54) **ORAL CARE IMPLEMENT**

- (71) Applicant: **Colgate-Palmolive Company**, New York, NY (US)
- (72) Inventors: **Takahide Okai**, Highland Park, NJ (US); **GuanMin Sun**, XiaMen (CN)
- (73) Assignee: **Colgate-Palmolive Company**, New York, NY (US)
- (**) Term: **15 Years**
- (21) Appl. No.: **29/697,651**
- (22) Filed: **Jul. 10, 2019**

(57) **CLAIM**

The ornamental design for an oral care implement, as shown and described.

DESCRIPTION

FIG. 1 is a front right perspective view of an oral care implement according to the new design;
FIG. 2 is a front view thereof;
FIG. 3 is a rear view thereof;
FIG. 4 is a right side view thereof;
FIG. 5 is a left side view thereof;
FIG. 6 is an enlarged top view thereof; and,
FIG. 7 is an enlarged bottom view thereof.

1 Claim, 4 Drawing Sheets(56)
